MULTIBLADE FAN CONSTRUCTION

Beecher B. Cary and Charles Hollerith, Jackson,
Mich., assignors to Hayes Industries, Inc.,
Jackson, Mich., a corporation of Michigan

Application June 16, 1936, Serial No. 85,458

7 Claims. (Cl. 170—159)

The present invention relates to improvements in multi-blade fans of the propeller or screw type and is particularly concerned with those used in connection with a cooling system of an engine

5 in an automotive vehicle.

Our invention is concerned with the economical manufacture of fans employing the principle of construction disclosed in U. S. Patent to Geise, No. 1,983,606, granted December 11, 1934, and is

10 considered to be an improvement thereon.

As disclosed at length in the aforesaid patent, so-called fan "noises" have been materially reduced by spacing adjacent pairs of blades different from following adjacent pairs. Tests have 15 shown us that the greatest reduction in noise over prior construction is obtained with each blade of the fan spaced a different arcuate distance from each adjacent blade. Where a multi-blade fan is desired with each blade unequally spaced from its adjacent blades, the balancing of the same in 20 production becomes a problem. In the copending application Serial No. 79,949, filed May 15, 1936 by Beecher B. Cary, one of the joint applicants in this application, the problem of balancing has 25 been solved by associating two separate inherently balanced fan units into a single unitary fan construction.

By the present invention, the desired result has 30 been obtained with a single unit which is placed in balance by the grouping of two or more blade parts of similar weight and configuration to counterbalance the inherently unbalanced condition resulting from the unequal spacing of all the blades of the fan.

35 Thus it becomes the object of the invention to provide a fan of the character described in which blades of equal weight are so spaced and grouped as to provide a balanced unit.

Another object is to provide a fan construction 40 having a central spider with radially disposed arms upon which the blades of the fan are supported in which the spacing of the blades is such that with blades of equal weight the unbalanced condition of the fan may be put in balance by 45 associating an additional blade of identical construction upon one or more of the blades of the fan.

A further object is to provide a fan having 50 unequally spaced radially disposed blades of similar weight and construction, in which the center of mass of the unbalanced fan is such with reference to one of the blades of the fan as to be moved to the axis of rotation by associating an additional blade of similar construction and weight with that 55 particular blade.

In the accompanying drawing wherein a single embodiment of the invention is considered to be sufficient to clearly illustrate the principles of the invention,

Fig. 1 is a side elevational view of the fan supported for rotation upon a suitable hub, 5

Fig. 2 is a front elevational view of the fan construction shown in Fig. 1 removed from its supporting hub, and

Fig. 3 is a fragmentary exploded view of one 10 of the blades of the fan shown in Fig. 2 showing the counterbalancing blade.

In the manufacture of parts of automotive vehicles the quantity produced is great and highly competitive with the result that, particularly with 15 reference to the manufacture of fans, every possible economy in labor and material must be effected. In view of this situation the assembly of the fan must be simple and of a character resulting in a unit balanced within the range of permitted tolerances. Reduction in cost of construction may also be obtained by reducing the number of different parts to a minimum particularly in the case of a sheet metal construction in which 20 expensive dies must be built and maintained. 25

According to the present invention an inexpensive commercially acceptable fan of the general type disclosed in the above mentioned patent has been provided which comprises a sheet metal spider 10 adapted to be suitably supported on the 30 hub 12 on the fan shaft in a well known manner. Radially disposed arms 14, 16, 18, and 20 unequally spaced about the center of rotation of the fan are deflected to give the desired pitch and carry the blades 22, 24, 26, and 28 which are 35 riveted or otherwise suitably attached. The blades are preferably of sheet metal with the blades 22, 24, and 26 each made up of a single part while the blade 28 is made up of two sheet metal parts 30 and 32 superimposed upon each 40 other and attached to the arm 20 in the same manner as the remaining blades. It is to be understood that preferably the single blades 22, 24, and 26 and the parts 30 and 32 making up the 45 blade 28 are all stamped out on the same die and from stock of the same gauge. Also the spider 10 is preferably in balance and in the illustrated embodiment this is accomplished by making the arm 20 larger and longer than the remaining arms and by employing an additional rivet. 50

Without limiting the invention to a four bladed fan or to employing a single blade part for counterbalancing the unit as we contemplate constructions of five or more blades and the use of one or more counterbalancing blade parts super- 55

imposed upon one or more single blades of the fan, in one commercial form of the invention now being used the blades are spaced in the following manner: Blades 22 and 24 are spaced 42° 5 11.5'; blades 24 and 26 are spaced 76° 22.3'; blades 26 and 28 are spaced 112° 22.7'; and the blades 28 and 22 are spaced 129° 3.5'. With this spacing arrangement of the blades 22, 24, and 10 26 which are of equal weight, the same are counterbalanced by the blade parts 30 and 32 which go to make up the two-ply blade 28.

From the foregoing description it will be apparent that the balanced fan consists of only two different parts; the spider 10 and the blade parts 15 22, 24, 26, 30, and 32 all of which are identical except for the rivet holes in the parts 30 and 32. In addition the extra blade part 32 does not change the appearance of the fan to any noticeable extent nor does it interfere with the air 20 stream of the same as would known types of counterbalancers generally used in counterbalancing the out of balance forces of rotating bodies.

Having thus described our invention what we
25 desire to protect by Letters Patent and claim is:

1. A multi-blade fan having a plurality of irregularly spaced single blade parts and an extra similar blade part acting as a counterbalance for the fan associated with one of said single blade parts, all of said blade parts being substantially identical in size, configuration, and gauge of material.

35 2. A multi-blade fan having a sheet metal central spider with radially disposed irregularly spaced arms, single blade parts carried by said arms, and an extra similar blade part acting as a counterbalance for the fan associated with one of said single blade parts, all of said blade parts being substantially identical in size, configura-
40 tion, and gauge of material.

3. A multi-blade fan having a sheet metal central spider with irregularly spaced radial arms, blade parts supported from said arms, the configuration of said spider and blade parts and the distribution of the mass thereof being such as to dispose the center of mass of the fan to one side of the axis of rotation and diametrically opposite one of said blade parts and an extra similar blade part superimposed upon said last blade part and functioning to shift the center of mass of the fan to its axis of rotation to balance the same, all of said blade parts being substantially identical in size, configuration, and gauge of material.

4. A multi-blade fan having a central blade supporting structure, a plurality of similar single blade parts irregularly spaced about said structure, the center of mass of said structure with said blade parts attached being disposed to one side of the axis of rotation of the fan and substantially diametrically opposite one of said blade parts, and an extra blade part imposed upon said last blade part and functioning to shift the center of mass of the fan to the axis of rotation to balance the fan, all of said blade parts being substantially identical in size, configuration, and gauge of material.

5. A multi-blade fan comprising a balanced central blade supporting structure, a plurality of blades spaced about said structure, certain of said blades being of equal mass and similar configuration and being irregularly spaced with reference to one of said blades as to be counterbalanced as a group by said last blade when of twice the mass of said certain blades, said last blade being constituted by two imposed blades each corresponding to said certain blades. 15 20

6. A multi-blade fan comprising a balanced central blade supporting structure, a plurality of similar blade parts supported from said structure, two of said blade parts being imposed upon each other to provide a two-ply blade, the remaining blade parts all being relatively spaced about said structure with reference to said two-ply blade part, the spacing of said remaining blade parts being such as to be balanced as a unit by said two-ply blade, all of said blade parts being substantially identical in size, configuration, and gauge of material. 35

7. A four blade fan comprising a balanced central blade supporting structure, five blade parts substantially identical in mass and configuration supported from said structure at equal distance from the center of rotation of the fan, two of said blade parts being imposed one upon the other to constitute a single blade while the remainder of said blade parts are separately employed to constitute the remaining blades of the fan, said blades being irregularly spaced from each other commencing with said two part blade as follows: of the order of 112° 22.7', 76° 22.3', 42° 11.5' and 129° 3.5', whereby said two part blade counterbalances the remaining blades to place said fan in balance. 40 45 50
